UNITED STATES PATENT OFFICE

HARRY M. YOUNG, OF WEBSTER GROVES, MISSOURI, ASSIGNOR TO WESTERN WIRE PRODUCTS COMPANY, OF ST. LOUIS, MISSOURI, A CORPORATION OF MISSOURI

WIRE FENCE FASTENER

Application filed June 23, 1930. Serial No. 463,135.

This invention relates to a certain new and useful improvement in wire fence fasteners. More particularly, my invention relates to a fastener especially, though not exclusively, adapted for attaching wire fencing to steel fence posts and the like.

My invention has for its chief objects to provide a fastener of the type described having a wide range of usefulness and selectively, adaptable in a simple manner for highly efficient employment in its intended purpose on most, if not all, of the commercial types of steel fence-posts, and to provide a fastening device of the kind set forth readily applied and adapted to be securely attached and fixed to a fence-post in a highly simple, efficient, practical, and inexpensive manner.

And with the above and other objects in view, my invention resides in the novel features of form, construction, arrangement, and combination of parts hereinafter described and pointed out in the claims.

In the accompanying drawings,—

Figure 1 is a fragmentary elevation of a wire fence, the strands of which are attached to the face of a T-shaped fence-post by means of fasteners of my invention;

Figure 2 is an enlarged fragmentary cross-sectional view of the fence of Figure 1, the strand being shown by dot-dash lines in partially applied position;

Figure 3 is an enlarged fragmentary face view of a so-called studded-T fence post, illustrating the use therewith of a strand-fastener of my invention;

Figure 4 is an enlarged fragmentary cross-sectional view of a so-called slotted-T fence-post, also illustrating the use therewith of a strand-fastener of my invention;

Figure 5 is a fragmentary face-view of the fence of Figure 4;

Figure 6 is an enlarged fragmentary elevation of a so-called angle fence-post, similarly illustrating the use therewith of a strand-fastener of my invention;

Figure 7 is a longitudinal sectional view of the fence of Figure 6; and

Figure 8 is an enlarged detail view of the strand-fastener.

Referring now more in detail and by ref-

erence characters to the drawings, which illustrates a preferred embodiment of my invention, the fastening device or fastener A is preferably formed of a length of bendable wire or the like and comprises a section including a body portion intermediately arched or reversely bent, as at 1, and having longitudinally aligned legs 2 outstanding at or projecting from each side of the bend 1. The legs 2 terminate in opposed end portions 3, 4, disposed at an angle to the legs 2 oppositely to the arch or bend 1, said end portions or terminals 3, 4, being bendable under said legs 2, one of said terminals, as 3, co-operating with the adjacent leg 2 in the formation of a permanent hook 5, and the other of said terminals, as 4, being reversely crooked, as at 6, to form, as may be said, a snap or spring hook for the fastener, for a purpose presently appearing.

In Figure 1 is shown a fragment of wire-fencing B, which comprises, as will be understood, a reticulated structure including longitudinal strands or wires 7. The fencing B is attached to a suitable support or fence-post C of the form known as a T-shaped type, that is, having a flange 8 and a stem 9 rearwardly presented therefrom. As shown, the individual strands or wires 7 of the fencing B are each attached to the post C by means of one of the fasteners A. As shown in dot-dash lines in Figure 2, the fencing B being in desired position on the post C, a fastener A is hooked at its terminal 3 over one marginal portion or longitudinal edge of the flange 8, on one side of and adjacent a wire or strand 7. The fastener A is then disposed more or less obliquely crosswise of the wire 7, and the terminal 4 engaged with and snapped or sprung over another portion or the opposite margin of the post-flange 8 in such manner that the wire 7 is arched over and embraced between the bend 1 and the face of the flange 8 of the post C. The legs 2 hence attachably span the face of, and are engageable on opposite sides of the wire 7 with, the flange 8, and, the terminal 3 being already hooked on one side of the flange 8, the other terminal 4 is bent under the other side of the flange 8 for efficiently securing the fastener A and its

engaged wire 7 on the post C. Preferably the flange 8 is crimped or gripped between the legs 2 and terminals 3, 4, for rigidly securing the fastener A in located position on the post, 5 as shown in Figure 2.

In Figure 3 is shown another commercial form of fence-post C', known as a studded-T type, the flange 8' thereof having a medial series of outwardly presented studs or lugs 10 arranged conveniently for supporting the respective wires 7 of the fencing B, as shown. In other respects, the post C' is similar to the post C, and inasmuch as my new fastener A is employed in a like manner thereon, no 15 further description thereof is deemed necessary here, except to say that the studs 10 serve to locate the fasteners in spaced relation on the post and hence crimping of the fastener for such purpose may be omitted.

20 While in the fence-posts C and C', the fastener A substantially transversely spans the full width of the flange 8, in the form of fence-post D shown in Figures 4 and 5, the portion of the fence-post spanned by the fastener A is that between the diagonally opposed end walls of a series of slots 11 provided in the flange 12 of the post D. The post D is a commercial form known as a slotted-T type, and the slots 11 are longitudinally spaced therealong on alternate sides of the stem 13 thereof. It will at once be seen, however, that the fastener A is applied to the fence-post D in substantially the same manner and for the same purpose as set forth in 25 connection with the post C, the one terminal 3 being engaged with a wall of one slot 11 and the opposite terminal 4 being engaged with a wall of the next adjacent slot, the strands 7 being obliquely spanned by, and 30 accommodated by the arches or bends 1 of the respective fasteners, as shown.

And in Figures 6 and 7 is shown still another form of fence-post E, known as the angle-type, in which one leg 14 is provided 45 with a longitudinal series of spaced slots 15. Obviously, the fastener A is adapted to span the portion of the post E between the opposing end walls of the successive slots 15, and hence will be disposed substantially transversely of the wire 7 of the fencing B. The fastener A is, however, applied to the post E in substantially like manner and for like purpose as has been heretofore set forth in connection with the posts C and D.

55 It will be hence seen that my invention accomplishes its objects, and, as I have shown, the fastener A is, by reason of its unique and novel form and construction, adapted selectively to be employed for its intended purposes on most, if not all, of a wide variety of fence posts now in commercial use. The fastener A is thus substantially, with respect to the various types of fence-posts, universally interchangeable, and I might add that the 60 fastener A is preferably constructed of a

bendable wire or the like, whereby it is equally universally applicable on the fence-wire 7 in any position of angularity thereacross.

However, I do not wish to be limited in my invention to the embodiment illustrated, for it will be understood that changes and modifications in the form, construction, arrangement, and combination of the several parts of the fastener may be made and substituted for those herein shown and described without departing from the nature and principle of my invention.

Having thus described my invention, what I claim and desire to secure by Letters Patent is:

A wire-fence fastener constructed of a section of bendable wire and integrally comprising a body-portion intermediately arched and having longitudinally aligned legs projecting in opposed relation from the opposite sides of said arch, one of said legs arcuately terminating in an angularly disposed end-portion and forming with said end-portion a permanent fence-post engageable hook, and the other of said legs also arcuately terminating in an opposed angularly disposed end-portion, said second end-portion including a reversely crooked tip and forming with said second leg a spring-hook for snapwise engagement with a fence-post in opposed relation to 90 said permanent hook, said hooks being disposed in the plane of said body-portion.

In testimony whereof I have signed my name to this specification.
